UNITED STATES PATENT OFFICE.

BARTLEY H. KOLLMAN AND ELMER R. PHILLIPS, OF INDIANAPOLIS, INDIANA.

ADVERTISING SIGN.

Application filed March 28, 1927. Serial No. 178,883.

The object of our invention is to produce an advertising sign of a character which may be installed along highways and public places and may embody either a one or two-way display, the sign panels being interchangeable, removable and replaceable in a convenient and expeditious manner, and the sign generally being so constructed and arranged as to be at all times proportionate, 10 strong and capable of withstanding exposure.

In the accompanying drawing, forming part hereof, Figure 1 is a perspective of a sign embodying our improvements; Fig. 2 an elevation showing the inner side of one 15 of the panels and other parts; Fig. 3 a vertical sectional view taken on the dotted line 3—3 in Fig. 2; Fig. 4 a detail section on the dotted line 4—4 in Fig. 2; and Fig. 5 is an enlarged detail section showing locking 20 means which we may employ.

In said drawings the portions marked 5 indicate the vertical members or standards of our improved sign, which are preferably mortised, at 6, 7, to receive the ends of upper 25 and lower horizontal rails, 8, 9, respectively. The rails are fixedly secured by bolts, 10, 11, preferably passing through take-up plates, 12, adjustably secured by nuts, 13, and said rails are provided with longitudinal grooves, 30 14, 15, 14', 15', as indicated in Figs. 3 and 5, for a purpose to appear.

From the upper rail 8, and secured thereto by the bolts 10, we extend a diagonally arranged angle-iron brace embodying the 35 members, 17, through which an adjusting rod, 18, is projected, and its lower end is provided with locking nuts, 20, 21, said rod 18 passing through the upper rail, and being provided at its upper end also with locking 40 nuts, 22, 23, the nuts 23 being hidden and protected by an ornamental fixture, 24. The nuts 13 are sunk in the vertical members 5, as indicated in Fig. 2, and the sockets in 45 which they are secured may be filled with plugs, 25, so that the frame when finished has a smooth and neat appearance.

The panel, 28, which bears advertising matter, is made of sheet metal reinforced by battens, 29, 30, arranged about and intermediate its edges, and is first inserted in the groove, 15', in the upper cross rail 8, the operation being indicated by dotted lines in Fig. 3, its lower end being then forced inwardly so that it will slide into the groove 55 15 in the lower cross rail 9, its final position being indicated at 28' in Fig. 3, it being

understood, of course, that we usually employ two panels, one for each side of the frame, so that the brace 17, battens 29, 30, take-up devices 12, and other details of 60 workmanship, will be hidden from view, and the sign as a whole present a neat and ornamental appearance, as indicated in Fig. 1. While these panels will be retained quite securely in the grooves in the manner explained we prefer to lock them to the vertical members or standards 5, and this we accomplish by angle-iron keepers, as 34, which are slipped into the clearance between the standard and the end of the panel and 65 hooked onto screws, 35, by means of slots, 36, in the inner web of the angle-iron, so that the outer web, 37, thereof will lap along the outer side of the panel. By reference to Figs. 4 and 5 it will be seen that this method 70 of locking is simple and that the devices are largely concealed by the panels, but we may employ any suitable means for the purpose.

The grooves in the lower rail 9 are provided with openings, 40, through which an 75 implement may be inserted to contact with the lower edge of the panel so that the latter may be raised from the groove and removed.

In the manner described we provide a sign which may be changed at will by removing one or both panels and substituting others therefor, and by providing the frame with braces, as 17, and the adjusting rod 18, we are enabled to tighten the frame structure whenever required, or so adjust it as to prevent its parts from sagging or becoming distorted. As is well known considerable time is consumed in renewing painted advertising signs when substituting one advertisement for another, as it becomes necessary to 80 send sign writers to the installed signboards, or remove and convey signs to a workshop to be repainted or changed. By our improvement, however, when the frame has once been installed in the soil or otherwise, vehicles laden with sign panels may be driven to the signs along highways, the 85 panels removed and new ones inserted, and those which have been in use may be rewritten and reused repeatedly, and this advantage is of great importance, as when 90 advertisements are discontinued, which frequently occurs, our improved frame may be left intact, the panels bearing discontinued advertising removed, and those bearing 95 other advertisements inserted. The sign 100 illustrated in Fig. 1 contemplates a frame 105 110

structure designed to be fixedly secured in the soil, but we desire it to be understood that our improved sign embodying a panel retaining frame may be mounted in any suitable manner for displaying advertising.

5 We claim as our invention:

1. In an advertising sign, a frame comprising vertical members and grooved horizontal members connected to said vertical members, a panel insertible in and removable from the grooved horizontal members, a brace connected to the horizontal members, and a rod connected to the horizontal members and brace for adjusting the frame to 10 prevent distortion thereof.

2. An advertising sign embodying vertical members having mortices therein, horizontal members seated in said mortices, adjustable take-up plates mounted in the standards, 20 bolts connecting the take-up plates to the horizontal members, a brace connected to the horizontal members, and means connecting the horizontal members and brace to adjust said members for preventing disalignement 25 thereof.

3. In an advertising sign, vertical and horizontal members adjustably connected together, a panel, means in the horizontal members for detachably securing the panel 30 thereto, means interposed between the panel

and vertical members for locking the ends of the panel to said members, means for bracing the vertical and horizontal members, and means connecting the horizontal members and brace to adjust the vertical 35 and horizontal members against distortion.

4. In an advertising sign, a frame comprising vertical members and horizontal members, means for adjustably securing said members together, a panel removably attachable to the horizontal members, keepers for securing the ends of the panel to the vertical members said keepers being detachably secured to the vertical members and engaging the ends of the panel to prevent displacement thereof, a brace connected to the frame members, and means connected to the brace and to the frame for adjusting the brace to prevent distortion of the frame. 40 45

5. In an advertising sign, a frame, bracing means connected to the frame, means for adjusting the bracing means to prevent distortion of the frame, and panels secured to each side of the frame and concealing said 50 55 bracing means.

In testimony whereof we affix our signatures.

BARTLEY H. KOLLMAN.
ELMER R. PHILLIPS.
